UNITED STATES PATENT OFFICE.

LAWRENCE Y. SPEAR AND HUGO E. GRIESHABER, OF NEW LONDON, CONNECTICUT.

SUBMERSIBLE-BOAT CONSTRUCTION.

1,072,393.

Specification of Letters Patent.

Patented Sept. 2, 1913.

Application filed August 5, 1911. Serial No. 642,487.

To all whom it may concern:

Be it known that we, LAWRENCE Y. SPEAR and HUGO E. GRIESHABER, both citizens of the United States, residing at New London, county of New London, State of Connecticut, have invented certain new and useful Improvements in Submersible-Boat Construction; and we do hereby declare the following to be a full, clear, and exact description of the invention, such as will enable others skilled in the art to which it appertains to make and use the same.

The invention relates particularly to an improved navigating equipment, and arrangement of navigating stations, as well as to an improved structural arrangement and combination of parts comprising and inclosed within the upper midship section of a submersible vessel, such as a submersible 20 torpedo boat.

Among the objects of the invention are to provide a submersible vessel which when submerged may be navigated entirely from within the hull, and which is also preferably provided with an elevated navigating bridge on the superstructure, as well as with an intermediate pressure resisting tower adapted for use as a trimming or surface navigating station; to provide a construction where- 25 in the hull may be completely separated by suitable closures from the projecting compartments thereon, including the fairwater and preferably the trimming tower, during submerged running, so that the presence of 30 any of the officers or crew within these projecting parts is not required during that time; to decrease the resistance of the projecting parts, especially while running submerged, by inclosing them in a tapered fair- 35 water in such a way as not to add buoyancy to the upper part of the vessel when submerged; to utilize this fairwater as a support for the navigating bridge; and to pro- 40 vide a passage, in addition to the passage 45 through the trimming tower, to the navigating bridge. In carrying out these objects, in the preferred manner, practically all of the many parts necessarily projecting above the hull of the vessel are inclosed in a 50 tapered housing so constructed as to constitute a fairwater which is intended to fill with water during submergence, and a hatch-trunk or passageway is provided through this housing from the main hatch 55 to the navigating bridge on top of the hous-

ing, which hatch-trunk is convertible from a water-tight passageway, when the main hatch-trunk is open, to a self-filling and emptying compartment of the fairwater, when the main hatch is closed. 60

We have illustrated the preferred form of the invention in the accompanying drawing in which—

Figure 1 represents a side elevation of the boat afloat; Fig. 2 a plan amidship on a 65 larger scale; Fig. 3 a section on line 3—3 of Fig. 2, and Fig. 4 a detail showing the hatch cover and scupper closure for the hatch-trunk.

As is customary in vessels of this type, the vessel shown has a strong hull A constructed to withstand the pressure of deep submergence, and a super-structure B running the length thereof and having a flat top serving as the main deck when the vessel is running 70 on the surface. Supported on the strong hull to constitute an upward projection therefrom, and itself so constructed as to withstand the pressure of deep submergence, is the observation tower C which in the present design is of small volume so as to afford room but for one or two men. This tower has at the base a contracted opening into the interior of the vessel, which opening is provided with a water excluding closure c, 75 whereby it may if desired be shut off from the interior of the vessel. Arranged about the upper end of the observation tower are a series of port holes d, constituting observa- 80 tion ports; and in the top of the tower is a 85 hatchway having the water excluding closure c'. The tower in general is to be used as a trimming station and is occupied by the commanding officer while filling the tanks, including the fore and aft trimming tanks, 90 preparatory to submergence. It may also be used as a navigating station. 95

The vessel is provided with two periscopes D and E both of which extend down within the hull of the vessel. The forward periscope is intended for the navigator, and with it he is enabled to navigate the vessel when submerged. The aft periscope is intended for the lookout, who is expected at all times to make the necessary observations of the entire horizon to detect the presence of any ships or obstructions with which the vessel might collide, and in time of war to keep a lookout for the enemy. 100

In order to provide an additional passage- 105

way from the interior of the hull to the bridge the main hatch F with its surrounding hatch-trunk H is provided.

To decrease the resistance in running, particularly in the submerged state, as well as to provide a hatch-trunk of a permanent nature, which does not have to be dismantled when the vessel is submerged, a housing G tapered at its forward and after ends 10 to constitute a fairwater, is built around practically all of the upwardly projecting parts, including the hatch-trunk, the top of the housing constituting the navigating bridge capable of accommodating a number 15 of persons. This housing or fairwater is supported on the superstructure B and is open to the sea so that when the vessel is submerged it is filled with water and does not increase the buoyancy. In the construction 20 shown the hatch-trunk H is formed by partitioning off the portion of the fairwater immediately above the hatch, so that the hatch-trunk constitutes a part of the housing. The hatch is provided with the usual 25 hatch cover F having mechanism for locking it in the closed position. In order that the hatch-trunk may also fill with water when the vessel is submerged it is provided with one or more scupper holes e. As best 30 shown in Fig. 4, the scupper hole has a cover e' operatively connected to the hatch cover F in such a manner that when the hatch-cover is open the scupper is closed and when the hatch cover is closed the scupper is open. 35 As a result of this construction the water is excluded from the hatch-trunk so long as the hatch cover is open, but during submergence, when the hatch cover is closed, the hatch-trunk is open to the sea and is, like 40 the fairwater, self-bailing and self-filling. The top of the hatch-trunk may be closed by the hinged cover-plate h, which is made 45 strong enough to constitute a part of the navigating bridge when it is in the closed position.

As will be seen the entire top of the housing G is flat, so as to constitute a navigating bridge, and is preferably provided in the region of the observation tower with the laterally extending platform g which may be folded back when desired. In convenient 50 position on this navigating bridge is mounted a standard O supporting an electrical steering gear controller, hand gear and compass, as well as an engine room telegraph, so 55 that the vessel may be navigated from the bridge. In the preferred construction this standard is made part of an upstanding fairwater M surrounding the forward periscope; 60 and the aft periscope is surrounded by a like upstanding fairwater N as shown.

Forward and aft ventilators, K and L, leading to the interior of the hull are also enclosed within the housing G as shown, and 65 these ventilators will be provided in the

usual way with emergency closing valves at the point where they pass through the hull.

It will be understood from the foregoing description that when the vessel is running on the surface it can be navigated from the bridge without the use of the periscope. In order to put the vessel in condition for submergence it is only necessary to dismantle the temporary railings about the bridge and the deck of the boat, the hatches and ventilators of course being closed before the vessel is completely submerged. During the initial operation of filling the main submergence tanks, which will ordinarily bring the water line to above the level of the main deck, and the operation of bringing the vessel to an even keel by admitting water in proper proportion to the forward and aft trimming tanks, an officer will be stationed in the observation tower C to observe the degree 70 of submergence and the trim of the vessel and to give the necessary orders for the proper filling of the tanks. After submergence the officer may retire from the observation tower, closing the hatch e to shut off 80 the passage from the tower to the interior of the vessel, if desired; and the vessel will then be navigated by the officer stationed at the periscope E. In this way we provide a vessel which may be navigated with the 85 maximum safety when submerged, and which may be navigated with the maximum convenience when running on the surface, and this is attained by a permanent structure available for use as a navigating bridge, 90 and affording free passage from the bridge to the interior of the vessel when on the surface, which structure is nevertheless of such character that it does not increase the buoyancy submerged and therefore does not require the provision of additional ballast to 95 destroy such buoyancy.

While the tower is primarily intended as a trimming station only it may be equipped with navigating adjuncts and used as a 100 navigating station.

What we claim is:

1. In a submersible vessel, the combination with a water-tight hull constructed to withstand the pressure of deep submergence, and an upstanding observation tower also constructed to withstand such pressure, of upstanding periscope tubes and ventilators outside of said tower, and a self-bailing and self-filling housing shaped to constitute a 115 fairwater about said tower, periscopes and ventilators.

2. In a submersible vessel, the combination with a water-tight hull constructed to withstand the pressure of deep submergence, and an upstanding observation tower also constructed to withstand such pressure, of upstanding periscope tubes and ventilators outside of said tower, and a self-bailing and self-filling housing shaped to constitute a 125 130

fairwater about said tower, periscopes and ventilators, said housing having a flat top constituting a navigating bridge.

3. In a submersible vessel, a strong hull 5 constructed to withstand the pressure of deep submergence, an upstanding self-bailing and self-filling housing thereon shaped to constitute a fairwater, a navigating bridge on top of said housing, and an observation 10 tower about which said housing is built, constructed to withstand the pressure of deep submergence and communicating with the hull.
4. In a submersible vessel a strong hull 15 constructed to withstand the pressure of deep submergence, an upstanding self-bailing and self-filling housing thereon shaped to constitute a fairwater, a navigating bridge on top of said housing, a trimming tower 20 about which said housing is built, said tower having observation openings and being constructed to withstand the pressure of deep submergence and communicating with the interior of the hull, and a navigator's periscope 25 extending through said housing into the interior of the vessel to a navigator's station.

5. In a submersible vessel a strong hull constructed to withstand the pressure of 30 deep submergence, an upstanding self-bailing and self-filling housing thereon shaped to constitute a fairwater, a navigating bridge on top of said housing, a trimming tower about which said housing is built, said tower 35 having observation openings and being constructed to withstand the pressure of deep submergence and communicating with the interior of the hull, a navigator's periscope extending through said housing into the interior 40 of the vessel to a navigator's station, and a supplemental periscope also extending through said housing into the interior of the vessel for the use of a lookout.

6. A submersible vessel having a strong 45 hull adapted to withstand the pressure of deep submergence, an elevated navigating bridge, a self-bailing and self-filling housing shaped to constitute a fairwater and supporting said bridge, an observation tower 50 about which said housing is built, a hatch in the hull and a hatch-trunk within the housing leading from the hatch to the bridge.

7. A submersible vessel having a strong 55 hull adapted to withstand the pressure of deep submergence, an elevated navigating

bridge, a self-bailing and self-filling housing shaped to constitute a fairwater and supporting said bridge, an observation tower about which said housing is built, a hatch in the hull, a hatch-trunk within the housing leading from the hatch to the bridge, 60 said hatch trunk being likewise self-bailing and self-filling when the hatch is closed, and a closure for the hatch within the hatch trunk.

8. A submersible vessel having a strong hull adapted to withstand the pressure of deep submergence, an elevated navigating bridge, a self-bailing and self-filling housing shaped to constitute a fairwater and 70 supporting said bridge, an observation tower about which said housing is built, a hatch in the hull, a closure for the hatch, a hatch trunk within the housing leading from the hatch to the bridge, a scupper in the hatch 75 trunk, a closure for said scupper, and connections for closing the scupper when the hatch is open and opening it when the hatch is closed.

9. In a submersible vessel, the combination 80 with a hatch and cover therefor, of a hatch trunk upstanding from said hatch and provided with a scupper, and a closure for said scupper connected to and adapted to be actuated by said cover to be closed when said 85 hatch is opened and opened when the hatch is closed.

10. In a submersible vessel, the combination 90 with a water-tight hull having a hatch and cover therefor and upstanding observation tower, periscope tubes and ventilators, of a non-water-tight housing shaped to constitute a fairwater inclosing said hatch and surrounding said observation tower, periscope tubes and ventilators and providing a 95 raised navigation bridge and a hatch trunk within said fairwater and provided with scupper closures connected with said hatch-cover to open when said hatch-cover closes and vice versa, said hatch trunk forming a 100 passageway from said hatch to said navigating bridge.

In testimony whereof we affix our signatures, in presence of two witnesses.
